MOTOR DRIVE MECHANISM

Max Garbell, Chicago, Ill., assignor to Victor
Adding Machine Company, Chicago, Ill., a cor-
poration of Delaware

Application May 3, 1937, Serial No. 140,432

9 Claims. (Cl. 192—02)

This invention relates to a motor drive mechanism for adding machines or the like, and its purpose is to provide improved means for controlling the connections of the machines with 5 their source of power.

The adding machine illustrated to which the mechanism is attached requires a single revolution or cycle for its normal operation in which the type bars are set up for making an impression thereof and are then restored to their normal positions during the cycle. Provision is also made whereby a number of successive cycles may be had at the will of the operator.

The chief objects of the present invention are 15 the provision of mechanism adapted to be engaged and driven for a complete cycle under the driving power of a motor, and to be automatically disengaged and brought to rest in a pre-determined position upon the completion of the 20 cycle.

Another object is the provision of manually manipulative means for conditioning the mechanism at the starting operation of the machine, and which mechanism has connections cooper- 25 ating therewith for effecting the drive and automatically releasing the same upon the completion of the cycle.

And a further object is the provision of cushioning means engageable at the end of the cycle 30 for absorbing the shock to the stopping action of the mechanism.

In the accompanying drawings embodying my invention, I show the mechanism as being attached to an adding machine, but do not wish 35 to be limited to the operation and action solely to an attachment while all of the features embodied in these improvements will be substantially the same.

Figure 1 is a top plan view of an adding ma- 40 chine showing the casing of the machine broken away and my improved drive mechanism attached thereto.

Figure 2 is a longitudinal sectional view taken on the line 2—2 of Figure 1, showing the drive 45 mechanism in side elevation.

Figure 3 is an enlarged detail perspective view illustrating the tripping mechanism for effecting the starting and stopping of the mechanism.

Figure 4 is an enlarged side elevation of the 50 drive mechanism as viewed from the reverse side.

Figure 5 is a view similar to Figure 4 illustrating the drive mechanism in driving position and rotated approximately 190 degrees.

Figure 6 is an enlarged cross-sectional view 55 taken substantially on the line 6—6 of Figure 4.

Figure 7 is an enlarged detail perspective view of the drum co-acting with the mechanism and the adjustable means thereon; and

Figure 8 is an enlarged partial detail sectional view taken on the line 8—8 of Figure 5.

The mechanism includes a motor 10 which has a shaft 11 to which a helical pinion 12 is secured. The pinion 12 is in mesh with a helical gear 13 carried on a driven shaft 14 which is supported in a bracket 15 that is secured to the 10 motor 10 at 16. The driven shaft 14 extends outwardly of the bracket 15 and has a ratchet wheel 17 secured thereto. Outwardly of the ratchet wheel 17, the driven shaft 14 carries a drum 18 loosely pivoted thereon, and which drum 15 is held in position on the shaft 14 by means of a lock washer 19 secured in a recess 20 in the shaft 14. The drum 18 is arranged to be intermittently connected for turning movements with the ratchet wheel 17 and this drum carries 20 a stud 21 on which a dog 22 is pivotally carried, and which dog is preferably in the shape of a bell-crank being provided with an engaging ear 23 and a leg 24. A tension spring 25 has one end secured to the dog 22 and its other end secured to a pin 26 carried by the drum 18, and this spring 25 serves to urge the engaging ear 23 of the dog 22 for engagement with the ratchet wheel 17. The dog 22 is normally retained out 25 of engagement with the ratchet wheel 17 by a bell-crank arm 27 which is provided with an integral inwardly directed ear 28 that is normally in the path of the leg 24 of the dog 22. The bell- 30 crank arm 27 is pivotally carried on a stud 29 which extends from the side plate A of the ma- 35 chine and is controlled by a motor bar 30 for effecting the release of the dog 22 and of the drum 18. The ear 28 is normally in the path of the leg 24 of the dog 22 and a member 31 carried on the bell-crank arm normally preventing 40 movement of the drum. The member 31 is slid- 45 ably carried below the ear 28 on the bell-crank arm 27 and is guided on a pair of pins 32 and 33 extending into elongated slots 34 and 35 provided in the member 31. A spring 36 has one end se- 50 cured to the pin 33 and its other end secured to a pin 37 fixed to the slide. This spring 36 normally retains the member 31 with an ear 38 thereon readily engageable by a shoulder 39 formed by a notched-out portion 40 on the pe- 55 riphery 18a of the drum 18.

The bell-crank arm 27 has a link 41 pivoted thereto at 42, and this link has its free end connected at 43 to a depending arm 44 fixed ad- 55 jacent the side plate A to a shaft 45 that has

an inwardly directed arm 46 fixed thereto that is provided at its free end with an elongated slot opening 47 to receive a pin 48 carried on a depending portion 30a of the motor bar 30. The link 41 is also provided with an upwardly directed portion 41a which carries an insulated strip 49, and this portion 41a has one end of a tension spring 50 fixed thereto, and which spring has its other end fixed to a pin 51 carried in the side plate A of the machine. This spring 50 serves to urge the link 41 rearwardly or to the left as seen in Figure 1 to retain the bell-crank arm 27 positioned with its ear 28 in the path of the leg 24 of the dog 22 and the ear 38 of the member 31 in the path of the shoulder 39 of the drum. The insulated strip 49 is normally in the path of a contact point 52 which is carried on an insulated strip 53 supported on the side plate A of the machine, and this insulated strip also carries a companion point 54. These points 52 and 54 each have a lead 55 and 56, the lead 56 being connected directly to the motor, while the lead 55 extends to a source of power and a lead 55a connects the source of power with the motor. The drum 18 also carries a stud 57 to which one end of an operating link 58 is connected and which link has its other end connected at 59 to an oscillatory arm 60 fixed to the actuating shaft 61 of the machine.

In the operation of the device when used to drive an adding machine, the desired keys of the machine are depressed, and to obtain the result, the motor bar 30 is then depressed. The depression of the motor bar 30 will rock the arm 46 downwardly and rock the shaft 45 and the depending arm 44 therewith which exerts a pull on the link 41 and effects the closing of the contact points 52-54 to complete the circuit to the motor. This movement of the link 41 also rocks the bell-crank arm 27 on its stud 29 and carries the ear 28 thereof out of the path of the leg 24 of the dog 22 and the ear 38 of the member 31 out of the path of the shoulder 39 of the drum 18. When the leg 24 of the dog 22 is released, the spring 25 will rock the dog with the ear 23 thereof into engagement with the ratchet wheel 17. It will be noted that the circuit to the motor is closed simultaneously with the engagement of the dog with the ratchet wheel so that the parts driven by the motor will be started rather smoothly without a jolt or jar. As the ear 23 engages the ratchet wheel 17, it will effect the turning movements of the drum 18 to reciprocate the link 58 and oscillate the arm 60 to operate the machine.

The movement of the bell-crank arm 27 to carry the ears 28 and 38 out of engagement with the leg 24 of the dog 22 and out of engagement with the shoulder 39 of the drum 18 carries the ear 38 inwardly of the periphery 18a of the drum 18, and as the drum is rotated by engagement of the dog 22 thereon with the ratchet wheel 17, the ear 38 will then ride on the inner surface of the periphery 18a of the drum 18 and retain the bell-crank arm 27 in this moved position with the ear 28 out of engagement with the leg 24 of the dog to permit of its movement with the drum 18 for a cycle of operation. When at near the completion of the cycle, the notched-out portion 40 of the drum will have been carried past the ear 38 of the member 31 and at which time this ear will drop through the notched-out portion, being urged by the spring 50 operatively connected thereto through the link 41 and bell-crank arm 27, the movement of the bell-crank

arm 27 being limited by a pin 62 fixed in the side plate A. As the ear 38 drops through the notched-out portion 40 in the periphery 18a of the drum 18, the bell-crank arm 27 is then again in its normal position and the ear 28 thereof is again positioned in the path of the leg 24 of the dog 22 to be engaged thereby at the end of the cycle and carry the ear 23 of the dog out of engagement with the ratchet-wheel 17. This movement of the bell-crank arm 27 carries the link 41 therewith to break the circuit between the contact points 52-54, and the drum 18 will then coast until the shoulder 39 thereof engages the ear 38. When the ear 38 is engaged by the shoulder 39, the member 31 will be forced against the tension of its spring 53 to cushion the stopping action of the drum 18. This member 31 will then hold the drum against turning movements which in turn, holds the operating link 58 and oscillatory arm 60 to prevent movement of the actuating shaft 61.

The time at which the circuit is broken in each cycle of operation of the mechanism may be varied in accordance to the type of machine being driven thereby or in accordance with the speed it is desired to operate the machine. The means for controlling the time at which the circuit is broken comprises a member 63 which is preferably L-shaped and provided with a tongue 64 that has its inner edge undercut at 64a to slidably engage a coacting edge 65 provided in the notched-out portion 40. The top surface of the tongue 64 is arranged to fit flush with the inner surface of the periphery 18a of the drum and this member 63 is adjustable thereon by a bolt 66 carried in the member 63 and extending through a slot 67 in the drum.

The member 63 when adjusted toward the shoulder 39 provides for a relatively short distance of travel of the drum from the time the ear 38 drops off of this member 63 to break the circuit and the ear is engaged by the shoulder 39. The greater the distance between the member 63 and the shoulder 39, the sooner the circuit is broken and the drum 18 will coast a greater distance before its shoulder 39 engages the ear 38.

I claim:

1. A device of the character described, comprising in combination, a driven element having an electric motor for driving the same, and a member carried axially of the driven element, a spring-urged dog carried by said member and engageable with the driven element to drive the member therewith, control means comprising a rigid arm and a resilient arm normally in the path of said dog and member respectively, and manually manipulative means for effecting movement of said control means to simultaneously release the dog and member permitting said dog to be spring-urged for engagement with said driven element for causing the turning movements of said member with the driven element, the resilient arm of said control means serving to hold the rigid arm out of the path of said dog by sliding engagement with said member when moved by the manipulative means and to form a cushioning stop for said member and retain the dog out of engagement with the driven element in timed relation with a cycle of operation of the driven element.

2. A device of the character described, comprising in combination, a driven element, an electric motor for driving the driven element, a circuit for the motor including a switch normally open in the circuit, a member carried axially with

said driven element, a dog carried by said member for engagement with the driven element to drive said member with said driven element, a control member having a rigid arm and a resilient arm normally in the path of said dog and member respectively for holding them against movement and for simultaneously closing said switch to close the circuit, and manually manipulative means for effecting movement of the control member to close the switch in the circuit and for releasing said rigid and resilient arms from the dog and member whereby said dog will engage said driven element for causing said member to be turned thereby.

15 3. A device of the character described, comprising in combination, a driven element and an electric motor therefor including a circuit, a member carried axially with said driven element, a dog carried by said member for engagement with the 20 driven element, a control member comprising a rigid arm and a resilient arm normally in the path of said dog and member respectively for holding them against movement, manipulative means operatively connected with the control 25 member to close the circuit and for simultaneously moving said control member to release the rigid and resilient arms thereof from said dog and member respectively whereby said dog will engage said driven element to drive the member therewith.

30 4. A device of the character described, comprising in combination, a driven element having an electric motor for driving the same, a member arranged for turning movements with said driven 35 element and normally disengaged therefrom, a dog carried by said member and engageable with said driven element to drive the member therewith, a circuit for the motor including a switch, control means to close the circuit including a rigid 40 arm and a resilient arm in the path of said dog and member respectively, and manually manipulative means for controlling the control means to simultaneously close the switch and to release the rigid and resilient arms from said dog and member permitting the engagement of the dog 45 with said driven element to drive said member.

50 5. In combination, a machine, a motor for driving said machine, a driven element and a drum including engageable means carried by said drum forming a driving connection between said motor and said machine, means actuated by a common control for effecting the engagement of said engageable means with said driven element and to connect the motor with a source of power to drive 55 said driven element and drum, said means including a rigid arm and a resilient arm normally in the path of said engageable means and drum respectively whereby they are released by movement of said common control, said resilient arm 60 being arranged for sliding engagement with the

drum when released therefrom and for cushioning the stopping shock thereto upon a completion of a cycle of said drum.

6. A device of the character described, comprising in combination, a driven element having an 5 electric motor and a circuit therefor, a member arranged for turning movements with said driven element, a dog carried by said member and engageable with said driven element to drive the member therewith, means operable to close the 10 circuit and having a rigid arm and a resilient arm normally in the path of said dog and member respectively, manually manipulative means for controlling said operable means to simultaneously close the switch and to release said rigid and 15 resilient arms from said dog and member whereby said member will be driven by said driven element, and means on said member engaging the resilient arm and retaining the operable means for nearly a cycle of operation and to then release the same 20 to break the circuit and to release said dog and stop the drum at the end of the cycle.

7. In combination, a machine, a motor for driving said machine, a driven element, a drum having an opening therein including engageable 25 means carried by the drum forming a driving connection with the driven element between said motor and said machine, means including a rockable member actuated by a common control for effecting the engagement of said engageable 30 means with said driven element and to connect the motor with a source of power to drive said driven element and drum, the opening in said drum permitting of the movement of said rockable member, and means on said drum retaining the 35 said means and rockable member in actuated position for nearly a cycle of operation when moved by said common control and the opening in said drum permitting of the release of said means and rockable member to disconnect the 40 source of power and the engageable means from said driven element.

8. The combination of claim 7 hereof in which there is an adjustable member carried by said drum and coacting with the opening therein for 45 varying the size of said opening whereby the source of power may be disconnected at predetermined positions of rotation of said drum.

9. The combination of claim 7 hereof in which there are resilient means carried by said means 50 and coacting with said drum and serving to retain the source of power connected during the turning movements of the drum with the driven element and to pass through said opening in the drum to cut off the source of power and to position the 55 said means into the path of the engageable means to disengage the same from said driven element, said resilient means forming means to stop said drum and to cushion the same during the stop.

MAX GARBELL 60
